SCIENCE MEDALLION

Dorothy K. Allen, Libertyville, Ill., and Donald W. Carter, Lake Geneva, Wis., assignors to F. H. Noble & Company, Chicago, Ill., a corporation of Illinois

Filed Oct. 15, 1963, Ser. No. 76,985

Term of patent 14 years

(Cl. D29—11)

FIG. 1 is a front elevational view of a science medallion showing our new design;

FIG. 2 is a rear elevational view thereof;

FIG. 3 is an elevational view of the left side thereof as viewed in FIG. 1;

FIG. 4 is a top view thereof; and

FIG. 5 is an elevational view of the right side of the medallion as viewed in FIG. 1 and showing a portion thereof rotated to a different position.

We claim:

The ornamental design for a science medallion, substantially as shown.
